CLAIM

The ornamental design for a floor lamp, as shown and described.

DESCRIPTION

FIG. 1 is a top perspective view of a floor lamp showing my new design.

FIG. 2 is a bottom perspective view of a floor lamp.

FIG. 3 is a front view of a floor lamp.

FIG. 4 is a rear view of a floor lamp.

FIG. 5 is a left side view of a floor lamp.

FIG. 6 is a right side view of a floor lamp.

FIG. 7 is a top view of a floor lamp, shown enlarged in scale; and,

FIG. 8 is a bottom view of a floor lamp, shown enlarged in scale.

The broken lines in the drawings depict portions of the floor lamp that form no part of the claimed design.
